(57) **CLAIM**

The ornamental design for a mosquito killer, as shown and described.

DESCRIPTION

FIG. 1 is a front, right and top perspective view of a mosquito killer, showing my new design;

FIG. 2 is a front, right and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged detail view of the portion 9 in FIG. 1; and,

FIG. 10 is an enlarged detail view of the portion 10 in FIG. 1.

The broken lines shown in the drawing illustrate portions of the mosquito killer that form no part of the claimed design. The dash-dot broken lines in the application illustrate the extent of the enlarged views and form no part of the claimed design.
